UNITED STATES PATENT OFFICE.

JOHN F. DOYLE, JR., OF GARDEN CITY, AND MANUEL D. AVILLAR, OF NEW YORK, N. Y.,
ASSIGNORS TO GLOBE EFFICIENCY CORPORATION, INC.

FLUSHING APPARATUS.

1,234,643.

Specification of Letters Patent. Patented July 24, 1917.

Application filed November 27, 1916. Serial No. 133,525.

To all whom it may concern:

Be it known that we, JOHN F. DOYLE, Jr., and MANUEL D. AVILLAR, both citizens of the United States, and residents, respectively, of Garden City, in the county of Nassau and State of New York, and New York city, in the county and State of New York, have invented certain new and useful Improvements in Flushing Apparatus, 10 of which the following is a specification.

This invention relates to a flushing apparatus for urinals, sinks, and similar devices, which is actuated not manually as heretofore, but by means of a plunger adapted to 15 be engaged by the trunk of the operator at or near his waist line. The construction is furthermore such, that the plunger projects a distance in front of the bowl, so that access to the latter cannot be had, until the 20 water is turned on, thus greatly improving the sanitary conditions of lavatories in which the device is installed.

In the accompanying drawings:

Figure 1 is a side elevation of a flushing 25 apparatus embodying our invention;

Fig. 2, a vertical section partly in side view of the plunger and adjoining parts;

Fig. 3, a right hand end view thereof;

Fig. 4, a detail of the plunger;

Fig. 5, a detail of the flushing tank; and

Fig. 6, a side view partly in section of a modification of the invention.

Referring more particularly to Figs. 1-5, the numeral 1 represents the bowl of a urinal shown to be affixed to a wall or partition 2, and adapted to be flushed from tank 3 by a pipe 4. At a distance above bowl 2, there is arranged, a preferably squared, horizontally disposed plunger 5, which normally 35 projects a distance in front of the bowl and is here provided with a curved arm or pusher 6 adapted to be engaged by the body of the operator, preferably at or near the waist of the latter. Plunger 5 passes 40 through a correspondingly squared tubular guide 7 projecting rearwardly from wall 2, and fitted by a shoulder 8 into an annular opening of the latter within which the guide is centered. A face plate 9 made integral with shoulder 8, permits the guide

to be removably secured to wall 2, by means of screws 10, so that by removing the latter, the guide may be withdrawn. Plunger 5, is furnished at the front of wall 2 with a stop 11, that defines the length of 55 its stroke, and at the rear of the wall with a spring 12, that tends to normally advance the same. Suitable means are provided for operatively connecting the rear end of the plunger with the valve 13 of the flushing 60 tank, such means being by way of example, shown to consist of a cable 14 attached at one end to the plunger, thence passing over a pulley 15 of guide 7, and attached at its other end to the lever 16 which operates 65 the valve. But these means may obviously be varied without departing from the spirit of our invention.

In the normal position of the parts, spring 12, so advances plunger 5, that 70 pusher 6 is located a distance in front of bowl 1. Thus the operator on approaching the bowl will be intercepted by the pusher, and will be obliged to retract the same against action of spring 12, before gaining 75 access to the bowl. In this way, a proper flushing of the tank is automatically effected, each time the urinal is used, thus adding greatly to the cleanliness and sanitary conditions of the lavatory. 80

In Fig. 6, the invention is shown to be applied to a sink 17, the plunger 5, furnished with the forwardly extending guard 6, being here shown to operate the valve 18 of the water supply cock 19 by rods 20 and 85 bell crank 21, valve 18 being with this embodiment an equivalent of valve 13.

We claim:

1. A flushing apparatus comprising a bowl, a plunger arranged above the same, a 90 pusher carried by the forward end of the plunger and located normally a distance in front of the bowl, and a water supply valve operatively connected to the plunger.

2. A flushing apparatus comprising a 95 bowl, a plunger arranged above the same, a pusher carried by the forward end of the plunger, a spring adapted to advance the plunger, a plunger guide normally a distance in advance of the bowl, and a water sup- 100

ply valve operatively connected to the plunger.

3. A flushing apparatus comprising a bowl, bowl supporting means, a spring-influenced plunger arranged above the bowl and projecting normally a distance in front of the bowl, a tubular guide engaged by the

plunger, a face plate on the tubular guide, said face plate being adapted to be removably attached to the bowl supporting means, 10 and a water supply valve operatively connected to the plunger.

JOHN F. DOYLE, JR.
MANUEL D. AVILLAR.
